US00D692902S

(12) **United States Design Patent** (10) **Patent No.:** **US D692,902 S**
Groene et al. (45) **Date of Patent:** **** Nov. 5, 2013**

(54) **INPUT DEVICE FOR AN ELECTRONIC TABLET**

(71) Applicant: **Microsoft Corporation**, Redmond, WA (US)

(72) Inventors: **Ralf Groene**, Kirkland, WA (US); **Hua Wang**, Sammamish, WA (US); **Katherine Bailey**, Seattle, WA (US); **James Alec Ishihara**, Bellevue, WA (US); **Karsten Aagaard**, Seattle, WA (US); **Anthony Reed**, Sammamish, WA (US); **J. David Schultz**, San Bruno, CA (US)

(73) Assignee: **Microsoft Corporation**, Redmond, WA (US)

(**) Term: **14 Years**

(21) Appl. No.: **29/448,270**

(22) Filed: **Mar. 11, 2013**

Related U.S. Application Data

(63) Continuation of application No. 29/422,123, filed on May 16, 2012, now Pat. No. Des. 678,277.

(57) **CLAIM**

The ornamental design for an input device for an electronic tablet, as shown and described.

DESCRIPTION

FIG. 1 is a top isometric view of an input device for an electronic tablet showing our new design;

FIG. 2 is a top view thereof;

FIG. 3 is a left side view thereof;

FIG. 4 is a right side view thereof;

FIG. 5 is a rear view thereof; and,

FIG. 6 is a front view thereof.

The broken line showing of various features on the input device for an electronic tablet is for environmental purposes only and forms no part of the claimed design.

1 Claim, 3 Drawing Sheets
